(57) **CLAIM**

The ornamental design for a percussive massage tool, as shown and described.

DESCRIPTION

FIG. 1 is a top front perspective view of a percussive massage tool shown in accordance with my new design; FIG. 2 is a bottom front perspective view of the percussive massage tool shown in FIG. 1;

FIG. 3 is a top rear perspective view of the percussive massage tool shown in FIG. 1;

FIG. 4 is a bottom rear perspective view of the percussive massage tool shown in FIG. 1;

FIG. 5 is a front elevation view of the percussive massage tool shown in FIG. 1;

FIG. 6 is a rear elevation view of the percussive massage tool shown in FIG. 1;

FIG. 7 is a right side elevation view of the percussive massage tool shown in FIG. 1;

FIG. 8 is a left side elevation view of the percussive massage tool shown in FIG. 1;

FIG. 9 is a top plan view of the percussive massage tool shown in FIG. 1; and,

FIG. 10 is a bottom plan view of the percussive massage tool shown in FIG. 1.

The features shown in broken lines are for the purposes of showing portions of the article which form no part of the claimed design.

1 Claim, 10 Drawing Sheets
